ATTORNEYS

UNITED STATES PATENT OFFICE.

LUCIUS E. WEAVER, OF EAST HAMPTON, CONNECTICUT, ASSIGNOR TO SUMMIT THREAD COMPANY, OF EAST HAMPTON, CONNECTICUT, A CORPORATION OF MAINE.

SEWING-MACHINE BOBBIN CASE.

1,423,056.

Specification of Letters Patent. Patented July 18, 1922.

Application filed February 28, 1921. Serial No. 448,687.

To all whom it may concern:

Be it known that I, LUCIUS E. WEAVER, a citizen of the United States, residing at East Hampton, in the county of Middlesex and State of Connecticut, have invented 5 new and useful Improvements in Sewing-Machine Bobbin Cases (Case B), of which the following is a specification.

This invention relates to a bobbin case 10 having a central post on which the tubular core of a universally wound bobbin is rotatable, the post being provided with a pivoted latch, adapted to confine a bobbin on the post, the latch constituting also an 15 element of means for ejecting or displacing the bobbin, all as shown by the Porter Patent No. 832,414, of October 2, 1906.

The object of the invention is to utilize 20 the above-mentioned latch to support a controlling device for yieldingly retarding rotation of the bobbin on the post, and preventing undesirably loose and free rotation of the bobbin without requiring limitation of the bulk of the winding of thread.

25 The invention is embodied in the improvements which I will now proceed to describe and claim.

Of the accompanying drawings forming 30 a part of this specification,—

Figure 1 is a plan view of a bobbin case having a bobbin-confining latch provided with a bobbin-controlling device embodying the invention.

Figure 2 is a section on line 2—2 of Figure 1.

In the drawings, 12 represents a bobbin case provided with a tubular post 13, having a longitudinal slot 14. A universally wound bobbin composed of a core 15 and 40 a winding 16 of thread is adapted to rotate loosely on the post 13. In the post is a spring-pressed plunger 17, having a bobbin-ejecting finger 18.

19 represents a latch pivoted at 20 to 45 the outer portion of the post 13, and having a cam-shaped arm 21, adapted to cooperate with the plunger 17 in holding the ejecting finger 18 in an inoperative position. The spring-pressed plunger cooperates 50 with the cam portion 21 in maintaining the latch in its operative position at right angles with the post, and in its inoperative position in alinement with the post, as in the said Porter patent.

55 The latch 19 is provided with a longi-

tudinally extending slot 22. To the latch is attached at one end of said slot, as by a rivet 23, a resilient tongue 24, extending along the slot 22, and having a free end portion normally projecting sufficiently below the latch to bear yieldingly on a portion of the outer end of the bobbin, as indicated by Figure 2.

When the latch is swung from the upright or inoperative position it occupies to 60 permit the application of a bobbin to the post, to the operative or bobbin-confining position shown by the drawings, the resilient tongue 24 is held by the latch in position to bear yieldingly on the outer end of 65 the bobbin and retard the rotation of the latter, so that the bobbin can rotate no faster than is required by the call of the thread. When the latch is in its operative position, it is held by the resilient means in 70 which the spring-pressed plunger 17 is included, against an edge portion of the case 12, as shown by Figure 2, and is slightly spaced from the bobbin, so that the pressure of the tongue 24 on the bobbin is due 75 wholly to the resilience of the tongue and not to the said resilient means. When the latch is swung to its inoperative position it displaces the tongue. The latch therefore performs two functions, in that it retains and releases the bobbin, and applies 80 and removes the resilient tongue.

It will be seen that the point of attachment 23 of the resilient tongue is out of the bobbin-containing space in the case, and that the free end portion of the resilient tongue conforms to the length of a bobbin of normal size, so that the employment of the tongue does not involve a reduction of 85 the bulk of the thread winding, and a reduction of the yardage of the thread therein.

The tongue 24 normally projects from the inner side of the latch when the latter is in its operative position, and is adapted to be 90 pressed into the slot 22 to any extent required by the length of the bobbin, so that a bobbin of maximum length and having a maximum yardage of thread may be interposed between the bottom of the case 95 and the latch. In other words, the length of the bobbin may be such that its outer end is separated from the inner side of the latch by a space of less width than the thickness of the tongue, it being necessary only to 100 105 110

prevent actual rubbing contact between the outer end of the bobbin and the latch. The tongue may therefore be made of any thickness desired, so that a tongue of maximum thickness does not require any reduction of the length of the bobbin. The edges of the slot support the edges of the tongue, so that there is no liability of edgewise displacement of the latter, hence a single rivet 10 23 is sufficient to attach the tongue to the latch.

I claim:

A sewing-machine bobbin case comprising a central tubular post, a bobbin-confining latch pivoted within the outer end of the bore of the post, and movable to an operative position at right angles with the post, and to an inoperative position in alignment with the post, said latch having a 15 cam-shaped arm at its inner end, means within the post for cooperation with said arm in yieldingly retaining the latch in either of said positions, the outer end of the

latch being positively supported by the case, when the latch is in its operative position, 25 said latch being provided with a longitudinal slot extending from the outer end portion to said arm, and an inherently resilient bobbin-controlling tongue fixed to the latch, at the outer end of said slot, and 30 extending lengthwise of the slot, the tongue being shorter than the slot, and its inner end normally projecting from the inner side of the latch, and arranged to bear yieldingly on the outer end of the core of 35 a universally wound bobbin when the latch is in its operative position, the tongue being adapted to be pressed into the slot by the bobbin, so that a bobbin of maximum length and yardage of thread may be confined by the latch and tensioned by the 40 tongue, the edges of the slot preventing edgewise displacement of the tongue.

In testimony whereof I have affixed my signature.

LUCIUS E. WEAVER.
